United States Patent Office.

TIMOTHY BAKER, OF ST. JOHNS, MICHIGAN.

Letters Patent No. 100,711, dated March 15, 1870.

IMPROVEMENT IN CHURNS.

The Schedule referred to in these Letters Patent and making part of the same

To whom it may concern:

Be it known that I, TIMOTHY BAKER, of St. Johns, in the county of Clinton, and State of Michigan, have invented a new and useful Improvement in Churn-Dashers; and I do declare that the following is a true and accurate description thereof, reference being had to the accompanying drawings and to the letters of reference marked thereon, and being a part of this specification, in which I give an elevation of my invention.

The nature of my invention relates to an improvement in churn-dashers, and consists in constructing the same of any suitable sheet metal, with a spiral flange surrounding and secured to a hollow standard, whose lower extremity terminates in a cone, with a solid base, the flange being in the form usually known as the Archimedean screw, and provided with a series of perforations.

In the accompanying drawings—

A represents a hollow standard, into the top of which a suitable handle may be inserted.

This standard terminates at its lower extremity in a hollow cone, B, with a closed or solid bottom.

Around this standard, and secured thereto, is a spiral flange, C, whose circumference should fit the interior of the churn-barrel, and which is provided with a series of perforations, a.

This dasher should be operated by a reciprocating motion, its peculiar form agitating violently the cream, and separating the fatty matter thereof from the globules in which it is contained with great ease.

When the butter "comes," it may be gathered by giving the dasher a rotary motion in the direction of the screw.

What I claim as my invention, and desire to secure by Letters Patent, is—

The churn-dasher above described, consisting of a hollow-standard, A, provided with a conical base, B, and a flange, C, attached to said base, and spirally arranged about the standard A, and provided with openings a, when constructed as described, and arranged to operate as and for the purpose set forth.

TIMOTHY BAKER.
